Cyrenius Lawrence

UNITED STATES PATENT OFFICE.

CYRENIUS LAWRENCE, OF CLYDE, MICHIGAN.

CRIB.

SPECIFICATION forming part of Letters Patent No. 400,693, dated April 2, 1889.

Application filed February 25, 1888. Serial No. 265,332. (No model.)

To all whom it may concern:

Be it known that I, CYRENIUS LAWRENCE, a citizen of the United States, residing in the township of Clyde, county of St. Clair, State 5 of Michigan, have invented certain new and useful Improvements in Cribs; and I do hereby declare the following to be a full, clear, and exact description of the invention, such as will enable others skilled in the art 10 to which it appertains to make and use the same.

My said invention relates to improvements in cribs adapted to be used in the construction of docks, breakwaters, and like purposes.

15 The object of my invention is to construct docks, breakwaters, and similar structures in such a manner that the timbers used as the walls of the crib will be held to the bottom of the water by the entire weight of the stones 20 or other material used in filling, and, further, to so construct the crib that the piles used may be driven through the same, thus making the crib, piles, and filling an entirety, no part being movable without the entire crib 25 also moving.

The particular construction, arrangement, and combination of the various parts of my said invention I will now proceed to point out and describe, reference being had to the 30 accompanying drawings, in which—

Figure 1 is a perspective of a crib constructed in accordance with my invention, ready to be filled, the piles being shown in position. Fig. 2 is a top plan view of the same.

35 Referring to said drawings, A represents the crib, the sides and ends of which are constructed with double walls B C, having a space between said walls open at the top and bottom. The timbers a of the inner walls 40 project across the space between the two walls and are interlocked with timbers of the outer wall. The entire structure is braced by cross-beams b, which are secured to the upper tier of the timbers of both the inner and outer walls and extend across the top of the inner and outer compartments of the crib. This bracing also serves to receive the 45 flooring or superstructure desired.

The compartment or space within the inner 50 walls is provided with a solid bottom or floor-

ing D, the timbers of which are of sufficient strength to bear the weight of the filling.

The crib is sunk by filling the inner compartment with stones or other suitable material, and when it is in the proper position piles 55 E are driven between the inner and outer walls. The piles at the corners of the inner walls are connected by chains F, which extend over the top of the projecting timbers a, thus securing the crib to the piles. When 60 the piles are driven, the space between said inner and outer walls is then filled with stone or other suitable material.

My invention possesses many advantages over the old forms of single-wall cribs. It 65 can be readily sunk at the desired point by simply filling the inner compartment with stone. The solidity given the crib and firmness with which it is held to the ground by the weight of the filling, which is borne by 70 the solid bottom of the inner compartment, prevents the force of the water from raising any part of the crib without moving the entire crib. The piles also, being driven in the space between the inner and outer walls and 75 being secured as described, are greatly strengthened, and their usefulness increased by the weight of the crib, which tends to hold said piles firmly in place, thus preventing all vibration and consequent weakening. 80

Having thus fully described my invention, I claim as new and desire to secure by Letters Patent—

1. The herein-described crib, having double walls, a space between said walls open at 85 the top and bottom, and a compartment within the inner walls, having a solid bottom, substantially as shown and described.

2. A crib having outer and inner walls, B and C, secured to each other by the projecting timbers a, a space between said walls open at the top and bottom, and a compartment within the inner walls, B, having a solid bottom, D, substantially as shown and described. 90

3. The combination, with the cribs having double walls, a space between said walls open at the top and bottom, and a compartment within the inner walls, having a solid bottom, of suitable piles driven between the inner and 95 100

outer walls of the crib, substantially as shown and described.

4. The combination, with the crib having inner and outer walls, B C, a space between 5 said walls open at the top and bottom, and a compartment within the inner walls, having a solid bottom, of suitable piles, E, driven between said inner and outer walls, the piles at

the corners of the compartment being connected by chains F, extending over the timbers a, substantially as shown and described. 10

CYRENIUS LAWRENCE.
